UNITED STATES PATENT OFFICE.

JOHN C. DUEBER, OF NEWPORT, KENTUCKY.

DESIGN FOR A WATCH-CASE.

SPECIFICATION forming part of Design No. 14,977, dated April 29, 1884.

Application filed December 31, 1883. Term of patent 7 years.

To all whom it may concern:

Be it known that I, JOHN C. DUEBER, a citizen of the United States, residing at Newport, in the county of Campbell and State of Kentucky, have invented a new and original Design 5 for Watch-Cases, of which the following is a specification, reference being had therein to the accompanying drawings.

The nature of the present design is clearly 10 and fully shown in the annexed drawings, in which—

Figure 1 is a front elevation of my ornamented watch-case, and Fig. 2 is an enlarged 15 transverse section of the band or center of said case.

A represents the band or center of an ordinary watch-case, which band is provided with a circumferential flange or rib, B, that occupies a position about midway between the 20 front and back of said band, as seen in Fig.

2. The flange B has a series of convexities or swells, C, and intermediate angular projections, D. These swells and angular projections may extend completely around the periphery of the center, or the continuity thereof may be interrupted at E. The front F may be of any appropriate finish, as it constitutes no part of my present design. 25

I claim as my invention—

The design for a watch-case herein shown 30 and described, the same consisting of a series of swells, C, arranged around the periphery of said case, and having angular projections D between said swells.

In testimony whereof I affix my signature in 35 presence of two witnesses.

JOHN C. DUEBER.

Witnesses:

JAMES H. LAYMAN,
SAM'L. S. CARPENTER.
